UNITED STATES PATENT OFFICE

WILMER H. BATH, OF WEST CONSHOHOCKEN, PENNSYLVANIA, ASSIGNOR TO THE SHARPLES SPECIALTY COMPANY, OF PHILADELPHIA, PENNSYLVANIA, A CORPORATION OF DELAWARE

CENTRIFUGAL MACHINE

Application filed October 10, 1928. Serial No. 311,561.

This invention relates to centrifuges and pertains more especially to devices for centrifugally separating liquids.

In such devices the separated liquids are 5 discharged from a rotating bowl in dispersed condition into stationary annular chambers, the inner edges of the top and bottom walls of which are spaced slightly from the upper surface of the bowl. Rotation of the bowl 10 causes rotation of the air surrounding it due to surface friction between the bowl and the air. The rotation of the air develops centrifugal forces therein which tend to cause a flow of air through the spaces between the 15 bowl and the edges of the chambers and also along the top and bottom walls of the chambers. As a result some of the liquids are carried by the air currents out of the compartment into which they were discharged from 20 the bowl. The liquids carried out of one chamber may be introduced into another chamber or into the casing of the centrifuge, thus causing either intermingling or loss of the separated liquids.

25 An object of this invention is to counteract the effect of the air currents above described and confine the liquids to the compartments into which they are discharged from the bowl.

30 Other objects, novel features and advantages of this invention will be apparent from the following specification and accompanying drawings wherein:

The figure is a vertical section of a centrifuge embodying the invention.

The casing of the device is designated by the reference character 10, and within this casing is rotatably mounted a bowl 11. This bowl is provided with a head 12 having passageways 13 and 14 through which the separated liquids are discharged in dispersed condition. The head is also provided with a neck 15 by means of which the bowl 11 is supported and rotated by suitable driving 45 means (not shown). A cover 16 surrounds the bowl 11 and is supported by the casing 10. A second cover 17 is supported from the first cover 16 and forms therewith a chamber into which liquid is discharged from the bowl 11 50 through the passageway 13. A lid 18 is sup-

ported by the cover 17 and forms therewith a chamber into which liquids are discharged from the bowl 11 through the passageway 14. The covers 16 and 17 are provided respectively with spouts 19 and 20 by means of which the liquids discharged into the chambers may be drained therefrom.

55 Rotation of the bowl 11 causes rotation of the air in contact therewith and the rate of rotation is substantially proportional to the diameter of the portion of the bowl in contact therewith. Where the rate of rotating of the air is greatest the air will have the greatest centrifugal force and vice versa. The centrifugal force in the casing will therefore be 60 greater than that in the chamber formed by the covers 16 and 17 which, in turn, will be greater than the centrifugal force developed in the chamber formed by the cover 17 and lid 18.

70 As a result there will be a tendency for air to flow from the upper chamber into the lower chamber and from the latter into the casing. There may be a flow of air in or out of either spout 19 or 20 according to the amount 75 of air which passes through the annular spaces. The air in contact with the surface of the bowl will have a greater angular velocity than the air in contact with the top and bottom walls of the chambers. Therefore, the air in contact with the top and bottom walls will have less centrifugal force 80 than the air midway therebetween and accordingly the rotating air will move inwardly 85 in a spiral direction along such walls and move outwardly in a spiral direction intermediate the walls.

90 The currents of air thus produced by rotation of the bowl tend to carry out from the chambers some of the atomized liquid suspended in the air therein as well as to carry liquid which has been deposited on the bottom and top walls of the chambers toward the inner edges of the covers from which it 95 may drop or be blown downwardly out of the chamber by the above described currents. As a result, liquids discharged into one of the chambers may be carried out therefrom into another chamber or into the casing of the 100

centrifuge, thus causing either intermingling or loss of the separated liquids.

According to this invention the flow of air from the lower chamber to the casing 10 is prevented by supporting an inverted frusto-conical collar 21 at the inner edge of the cover 16 and providing helical vanes 22 projecting from the inner face of the collar toward the bowl. The vanes decrease in width down- 19 wardly so that the inner edge of the vanes are equally distant from the axis of the bowl. The channels formed by the vanes of the collar are therefore of increasing cross section in upward direction. The upward slope 15 of these vanes is in the same direction as the direction of rotation of the bowl 11.

These vanes have a shearing effect upon the air rotated by the bowl 11. The shearing action of the vanes produces upward flow 20 of air in the channels formed by the vanes and the collar. The production of the upward flow of air is assisted by the upward and outward slope of the collar. The flow of air in the channels is therefore directed upwardly and outwardly across the top edge of the collar. This current of air tends to carry outwardly of the chamber any liquid which may be collected on the top edge of the collar as well as the atomized liquid in the vicinity 25 thereof. The air carried upwardly in this way is replaced by air from the casing which is provided with an air inlet (not shown). The current of air thus produced effectively prevents loss of liquid from the lower chamber 30 to the casing. The upward flow of air may be varied by variation in the dimensions of the vanes and the variation of the inlet to the casing.

The primary effect of this invention is to 40 prevent leakage of liquid from the lower chamber into the casing 10 by creating in the channels an upward pressure which counter-balances the downward pressure created by rotation of air in the casing 10. However, 45 the upward current of air produced according to this invention may be made sufficient to create a balance of conditions between the lower and upper chambers so that there is no current of air through the annular space connecting the two chambers. In this way, the 50 invention has the secondary effect of eliminating liquid leakage from the upper chamber to the lower chamber. Furthermore, if leakage in one direction is very objectionable 55 but is unobjectionable in the other direction the upward current of air may be made sufficient to prevent leakage in the objectionable direction although permitting it in the unobjectionable direction.

60 Although in the embodiments of the invention specifically disclosed herein, the collar 21 is supported by the cover 16 and prevents loss from the lower chamber to the casing, it is apparent that it is within the contemplation 65 of this invention that the collar be sup-

ported by the cover 17 for the purpose of preventing loss from the upper to the lower chamber. The invention can be made use of wherever it is desired to prevent loss from a discharge chamber of a centrifugal machine. 70

It is, of course, understood that various structural modifications may be made in the above disclosure without in any way departing from the spirit of the invention as defined in the appended claims. 75

I claim:—

1. In a centrifugal machine, a casing, a bowl rotatably mounted therein, covers forming chambers for receiving liquids discharged from said bowl, an inverted frusto-conical collar carried by one of said covers and helical vanes projecting from the inner face of the collar toward the bowl. 80

2. In a centrifugal machine, a casing, a bowl rotatably mounted therein, covers forming chambers for receiving liquids discharged from said bowl, an inverted frusto-conical collar carried by one of said covers and helical vanes projecting from the inner face of the collar toward the bowl, said vanes being of greater width at the top than at the bottom. 85

3. In a centrifugal machine, a casing, a bowl rotatably mounted therein, covers forming chambers for receiving liquids discharged from said bowl, an inverted frusto-conical collar carried by one of said covers and helical vanes projecting from the inner face of the collar toward the bowl, said vanes having their inner edges equi-distant from all points from the axis of the bowl. 90

4. In a centrifugal machine, a casing, a bowl rotatably mounted therein, covers forming chambers for receiving liquids discharged from said bowl, an inverted frusto-conical collar carried by one of said covers and helical vanes projecting from the inner face of said collar and forming upwardly extending helical channels. 105

5. In a centrifugal machine, a casing, a bowl rotatably mounted therein, covers forming chambers for receiving liquids discharged from said bowl, an upwardly flaring collar carried by one of said covers and means for imparting upward velocity to air rotating in the space between the collar and the bowl. 110

6. In a centrifugal machine, a casing, a bowl rotatably mounted therein, covers forming chambers for receiving liquids discharged from said bowl, an upwardly flaring collar carried by one of said covers and means within said collar for causing upward flow of air in the space between said collar and bowl. 120

In testimony whereof, I have signed my name to this specification.

WILMER H. BATH.
